METHOD OF LASTING SHOES

Filed Dec. 31, 1931

2 Sheets-Sheet 2

UNITED STATES PATENT OFFICE

EUCLID I. LA CHAPELLE, OF BROCKTON, MASSACHUSETTS

METHOD OF LASTING SHOES

Application filed December 31, 1931. Serial No. 584,184.

The term "bed" as applied to a lasting machine occurring in the specification and in the claims is to be interpreted to include wipers for lasting one or both ends of a shoe.

135 The term "shoe" occurring in the specification and in the claims is to be interpreted to include a shoe or boot partly made.

My novel method relates to the lasting of shoes and more particularly to the lasting 10 of such shoes as of the well known Goodyear welt and McKay types. In its broadest aspect, however, my method relates to the lasting of any and all types or kinds of shoes adaptable to its practice.

115 The lasting operation upon shoes of the Goodyear welt type as now being performed in the shoe factories in the United States involves the use of the following machines:

- (a) Assembling machine;
- (b) Pulling-over machine;
- (c) Side lasting machine; and
- (d) Bed lasting machine.

In lasting McKay shoes the bed lasting machine may be omitted as then the toe and the heel may be lasted as well by the side lasting machine.

125 The pulling-over operation is performed prior to lasting the shankpart of the upper and whether performed by hand or machine it involves the straining of the upper lengthwise of the last from the heel to the toe-end by grippers engaging and straining the toe-end 70 of the upper and thereafter by grippers engaging and straining the sides of the forepart of the upper.

135 Under such lengthwise strain at the toe-end of the upper, the vamp, and the seam uniting the vamp and the quarters of the upper, are forced away from the top of the forepart of the last, back of the toe, and then extra strain is required in lasting and setting the vamp and the said seam on the top of the last back of the toe, and with liability of irreparable damage to the vamp, its seams or its lining. Under the influence of the pulling-over operation, the vamp and the said seam along the shankpart of the upper are forced away from the bottom of the last so that extra strain is also required in lasting and setting the vamp and the said seam properly on the 80 last at the subsequent operation of lasting the

shankpart. Moreover, to thus strain the upper from the heel to the toe-end to the extent called for by the dictates of the best pulling-over practice, increases these defective conditions.

135 It is a well recognized fact that the most difficult part of lasting resides in the proper setting of the vamp of the upper on top of the forepart of the last, back of the toe, and of the setting of the seam uniting the vamp and the quarters at the throat of the vamp forwardly and firmly down on the last.

It is also a well known fact that unless the upper and the said seam uniting the vamp and the quarters be well strained and set lengthwise of the last from the heel to the ball line of the last, the shankpart cannot be properly lasted.

140 My novel method aims towards eliminating the objections noted at the pulling-over operation and towards making possible a better, more rapid and easier pulling-over operation and a better lasting operation at the forepart and at the shankpart of a shoe than heretofore possible, by eliminating the extra strain now required in lasting the forepart and the shankpart of the upper, by lasting, setting and fastening in lasted condition the upper and its seams on top of the forepart of the last, back of the toe, and along the shankpart, 75 preparatory to the pulling-over operation at the forepart.

145 My novel method further aims towards making possible the use of only two machines in the performance of the entire lasting operation and to this end I provide for the performance of the pulling-over operation at the forepart and of the toe and heel wiping operations by one setting on a bed lasting machine, by eliminating the objections noted at the ordinary pulling-over operation and also by making it possible to strain uppers having tips lengthwise of the lasts at the pulling-over operation to a predetermined extent relatively to the toe-end of the insoles, whereby all the tips in a given number of shoes will be uniform in length and in straightened position on the lasts in accordance with the particular swing of the lasts.

150 The bed lasting machine herein shown is

substantially the well known "Long bed lasting machine"; and the demarcation on the insole for length and straightness of tips is old in the art also; and no claim is made in this application except for the method.

As shown in the drawings:

Figure 1 represents a section of a welt shoe of the Goodyear welt type showing a last, and an insole, having a demarcation for length and straightness of tips, and a shoe upper assembled on the last;

Figure 2 represents a lasting machine adapted to strain a shoe upper lengthwise of a last; and the shoe shown in Fig. 1, is mounted thereon with the upper under lengthwise strain and with the shankpart in lasted condition;

Figure 3 represents a front view of the shoe upper straining means, showing the shoe upper engaging portion thereof covered with sole leather;

Figure 4 represents a side elevation of an ordinary bed lasting machine, showing the shoe shown in Fig. 2, thereon, in readiness to be pulled-over at the forepart and wiped at the toe and at the heel; and

Figure 5 is a plan view of the said bed lasting machine shown in Fig. 4, showing the shoe after the performance of the pulling-over operation and of the toe and heel wiping operations and showing the shoe entirely lasted.

Referring further to the drawings, I provide the last 1, and the Goodyear welt shoe insole 2, on which I provide a demarcation 2' for length and straightness of tips, and which I assemble to the last in the usual manner by the tacks 3, and I provide the shoe upper 4, which I assemble to the last in the usual manner by the tacks 5. The shoe is then in readiness for the shank lasting operation in accordance with my method for which I provide a machine adapted to strain the upper lengthwise of the last from the heel to the toe by the straining means embodied therein and which is adapted to engage the vamp of the upper at the top of the forepart of the last, back of the toe, and strain the upper by frictional contact therewith and thus hold the upper under lengthwise strain during the lasting of the shankpart. In this conjunction it is to be stated that the toe-end of the upper may be advantageously strained by the operator with hand pincers preparatory to and during the straining movement of the straining means so as to bring about a double straining action upon the upper from the heel to the toe of the last.

The said machine is provided with an adjustable jack-post 6, carrying an adjusting screw 6', whereby it may be adjusted relatively to the straining means 8, for various sizes of lasts. The last, upon which the insole and the upper are assembled, is mounted thereon and by forcing the said jack-post

against the spring 7, the forepart of the shoe is passed over the straining means which is then in the dotted position shown in Fig. 2. Then by depressing the treadle 9, against the action of the spring 10, the treadle-rod 11, is

raised, forcing the toggle 12, as shown in dotted lines Fig. 2, to the straightened position shown in full lines. The straining means

8, is thus moved toward of the last in the full line position shown whereby the upper

is strained lengthwise of the last from the heel to the toe. In this position the treadle

is locked by the spring pressed locking-lever

13, which holds the straining means in straining position whereby the upper is held under

lengthwise strain preparatory to and during

the shank lasting operation, after which op-

eration the operator releases the treadle by

pressing upon the locking-lever 13. For con-

venience to the operator, the upper portion

14, of the machine 15, carrying the shoe sup-

porting elements and the straining means, is

mounted to rotate about 180 degrees so as to

permit the operator to last both sides of the

shoe while remaining at one side of the ma-

chine. Abutments 16 and 17 are provided

to limit the rotation of the portion 14, of

the machine by contact with the pin 18. To

permit of such rotation of the portion 14, of

the machine, the treadle-rod 11, is positioned

in the center of the ball bearing race-way

19, and is provided with a ball and socket

joint 20. I provide a bed lasting machine 21,

shown in Fig. 4, and the shoe 4, as shown

partly lasted in Fig. 2, is mounted thereon in

readiness for the performance of the pulling-

over operation and of the toe and heel wiping

operations. The operator first sets the hold-

down 22, which is in the form of a flat spring,

over the bottom of the shoe and then forces

the heel-band 23, against the shoe by moving

the carriage, on which is mounted the hold-

down and the heel-band, and thus the hold-

down is forced on the bottom of the shoe in

the position shown in dotted lines 22', shown

in Figs. 4 and 5. Then the shoe being there-

by held firmly from movement, the pulling-

over operation is performed by hand and

then the upper is lasted at the sides of the

forepart and the ordinary toe and heel wip-

ing operations are thereafter immediately

performed and the shoe is shown entirely

lasted in Fig. 5.

More specifically explained, while the up-
per is being under lengthwise strain by the
straining means 8, the operator proceeds to
last the shankpart by means of ordinary hand
lasting pincers and in the usual manner by
first pulling and fastening in lasted condi-
tion the ends of the counter with the upper
and its lining and thereafter by pulling the
upper at each side of the last just below the
ball-line of the last by a bottomward diag-
onally toewards pulling movement; and after
thus lasting and fastening the upper in lasted

condition, he next pulls the upper and fastens the same in lasted condition at the ball of the last at both sides of the last. The vamp of the upper and its seams having thus been properly lasted, set and fastened in lasted condition on top of the forepart of the last, back of the toe, the operator proceeds with the lasting of the shankpart between the points already lasted and then, preferably by the aid of a "shank-laster" a well known tool so-called and which is most efficient for the purpose in both quality of workmanship and rapidity of operation. After the shank lasting operation, the vamp of the upper and its seams having been properly lasted, set and fastened in lasted condition from the heel-end to the ball line of the last, the shoe is thus properly prepared for the pulling-over operation at the forepart which should be performed so as to have the tip-seam of the upper in alignment with the demarcation 2' on the insole.

The present day commercial bed lasting machine could be substituted for the bed lasting machine herein shown.

It is a notable fact that the strain upon the upper lasted in accordance with my method is far less severe than heretofore so that only a few tacks are needed to hold the upper in lasted condition and a shoe of the Goodyear welt type, as herein shown, may be passed directly to a welt shoe sewing machine without need of substituting staples for the lasting tacks. Moreover, due to the mild strain in lasting shoes in accordance with my method, liability of damage to the upper, its seams or lining is quite remote.

A combination of the machine shown in Fig. 2, and of the machine shown in Fig. 4, might be possible and then the entire lasting operation would be performed by one setting; but I prefer to have, as herein shown, two separate machines, as once the shank lasting operation has been performed it is believed advisable to inspect the shoe while in natural position—bottom down.

It is to be appreciated that my method is intended to cover and does cover the lasting of the shankpart in whole or in part preparatory to the pulling-over operation at the forepart. For instance, in the event that the upper were lasted only at or just below the ball-line of the last, as in the initial step herein explained of lasting the shankpart preparatory to the pulling-over operation at the forepart, I then would consider my method as availed of; and my invention and the claims are to be interpreted in this broad sense.

A shoe lasted in accordance with my method will retain its original shape better than heretofore once the last has been removed and during the time of wear.

"Steam box-toes" (fabric material chemically treated and quite rigid) are in general

use and now call for two consecutive steaming operations and the second steaming renders the fabric material of such box-toes crisp and easy to crack or tear at toe wiping and during wear. Only one steaming operation is necessary when shoes are lasted in accordance with my method and by the two machines herein shown, as then the box-toe is steamed preparatory to the pulling-over operation at the forepart and the toe wiping operation following immediately thereafter, the box-toe is still in that state of softness adaptable to proper wiping. In pulling over by hand uppers embodying steam box-toes, a thick leather glove is usually worn on the left hand.

I want it well understood that my invention and this application are to be limited only by the prior art and as specifically stated in each claim.

Having thus explained the nature of my method and shown the best form of practicing the same now to me known, what I claim as new and desire to secure by Letters Patent of the United States is:

1. That method of lasting shoes which consists in providing a last, and an insole and a shoe upper assembled on the last; in engaging the vamp of the upper at the top of the forepart of the last, back of the toe, to strain the upper lengthwise of the last from the heel to the toe and thereby properly set the vamp and its seams on top of the forepart of the last, back of the toe; in thus straining the upper lengthwise of the last; and in then lasting and fastening in lasted condition the shankpart of the upper, while under lengthwise strain, preparatory to the pulling-over operation at the forepart.

2. That method of lasting shoes which consists in providing a last and an insole and a shoe upper assembled on the last; in straining the upper lengthwise of the last from the heel to the toe to a predetermined extent relatively to the toe-end of the insole; and in then lasting and fastening in lasted condition the shankpart of the upper, while under lengthwise strain, preparatory to the pulling-over operation at the forepart.

3. That method of lasting shoes which consists in providing a last, and an insole and a shoe upper assembled on the last; in straining the upper lengthwise of the last from the heel to the toe to a predetermined extent relatively to the toe-end of the insole; in lasting and fastening in lasted condition the shankpart of the upper, while under lengthwise strain, preparatory to the pulling-over operation at the forepart; and in performing the pulling-over operation at the forepart by re-straining the upper lengthwise of the last to a predetermined extent relatively to the toe-end of the insole.

4. That method of lasting shoes which consists in providing a last, and an insole and

a shoe upper assembled on the last; in straining the upper lengthwise of the last from the heel to the toe prior to lasting and fastening in lasted condition the toe-end of the upper; and in then lasting and fastening in lasted condition the shankpart of the upper, while under lengthwise strain, preparatory to the pulling-over operation at the toe-end.

5. That method of lasting shoes which consists in providing a last, and an insole and a shoe upper assembled on the last; in engaging the vamp of the upper at the top of the forepart of the last, back of the toe, to strain the upper lengthwise of the last from the heel to the toe and thereby properly set the vamp and its seams on top of the forepart of the last, back of the toe; in engaging the toe-end of the upper and in then straining the upper lengthwise of the last by simultaneously straining the upper at the toe-end thereof and at the top of the forepart of the last, back of the toe; and in lasting and fastening in lasted condition the shankpart of the upper, while under lengthwise strain, preparatory to the pulling-over operation at the forepart.

6. That method of lasting shoes which consists in providing a last, and an insole and a shoe upper assembled on the last; in engaging the vamp of the upper at the top of the forepart of the last, back of the toe, to strain the upper lengthwise of the last and thereby properly set the vamp and its seams on top of the forepart of the last, back of the toe; in thus straining the upper lengthwise of the last; in lasting and fastening in lasted condition the shankpart of the upper, while under lengthwise strain, preparatory to the pulling-over operation at the forepart; in passing the partly lasted shoe to a bed lasting machine and in then performing the pulling-over operation at the forepart and fastening the upper in pulled-over condition; and in then wiping and fastening in wiped condition the remainder of the unlasted upper.

7. That method of lasting shoes which consists in providing a last, and an insole and a shoe upper assembled on the last; in straining the upper lengthwise of the last from the heel to the toe; in then lasting and fastening in lasted condition the shankpart of the upper, while under lengthwise strain, preparatory to the pulling-over operation at the forepart; in passing the partly lasted shoe to a bed lasting machine and in then performing the pulling-over operation at the forepart and fastening the upper in pulled-over condition; and in then wiping and fastening in wiped condition the remainder of the unlasted upper.

8. That method of lasting shoes which consists in providing a last, and an insole and a shoe upper assembled on the last; in engaging the vamp of the upper at the top of the forepart of the last, back of the toe, to strain the upper lengthwise of the last from the heel to

the toe and thereby properly set the vamp and its seams on top of the forepart of the last, back of the toe; in thus straining the upper lengthwise of the last; in lasting and fastening in lasted condition the shankpart of the upper, while under lengthwise strain, preparatory to the pulling-over operation at the forepart; in passing the partly lasted shoe to a bed lasting machine and in then performing the pulling-over operation at the forepart by straining the upper lengthwise of the last to a predetermined extent relatively to the toe-end of the insole; and in then wiping and fastening in wiped condition the remainder of the unlasted upper.

In testimony whereof I have signed my name to this specification.
